UNITED STATES PATENT OFFICE

93,026

DESIGN FOR A BRUSH

Max C. Krenz, Ridgeland, Wis.

Application May 12, 1934, Serial No. 51,759

Term of patent 7 years

To all whom it may concern:

Be it known that I, MAX C. KRENZ, a citizen of the United States, residing at Ridgeland, in the county of Dunn and State of Wisconsin, have invented a new, original, and ornamental Design for a Brush, of which the following is a specification, reference being had to the accompanying drawing, forming part thereof, wherein:—

Fig. 1 is a side elevation of a brush showing my new design; and

Fig. 2 is a plan view of the same.

I claim:—

The ornamental design for a brush substantially as shown.

MAX C. KRENZ.
